JEWELRY

Gaston Candas, New York, N. Y.

Application December 13, 1935, Serial No. 54,174

10 Claims. (Cl. 63—1)

This invention relates to jewelry and particularly to bracelets comprising detachable articulated sections adapted to be used separately as decorative elements. Articles of jewelry are luxuries, and consequently little attention has been paid heretofore to multiple use of particular articles. Such articles have been designed usually only for one purpose. Bracelets are intended to decorate the arm of the wearer. Brooches and 10 clips likewise have their particular uses.

It is the object of the invention to provide a bracelet, articulated sections of which may be separated or connected readily for individual or combined use, the sections being provided with 15 independent fastening means whereby they may be secured to fabrics and the like.

Another object of the invention is the provision of decorative clips having normally invisible means associated therewith whereby the clips 20 may be articulated to form a bracelet.

Other objects and advantages of the invention will be apparent as it is better understood by reference to the following specification and accompanying drawings, in which

25 Fig. 1 is a plan view partially in section of a bracelet embodying the invention;

Fig. 2 is an elevation of the rear side of one of the bracelet elements;

Fig. 3 is a similar view of another element; 30 Fig. 4 is a sectional view on the line 4—4 of Fig. 1;

Fig. 5 is a sectional view on the line 5—5 of Fig. 4;

Fig. 6 is a sectional view indicating the disposal 35 of one of the articulating devices in concealed position;

Fig. 7 is a transverse section through another of the articulating devices;

40 Figs. 8 and 9 are views in perspective of two co-operating ends of contiguous elements of the bracelet; and

Fig. 10 is a sectional view indicating the use of one of the bracelet elements as a clip.

45 It will be understood that in carrying out the invention many modifications may be made in the details of structure and of ornamentation of the bracelet elements 5 and 6, which may, for example, consist of connected links 7 of metal or other suitable material. The links may be ornamented with engraving or filigree and may support precious, semi-precious, or artificial stones 50 8. At one end of each of the sections 5 and 6 are members 9 and 10 which may be similarly 55 ornamented.

The members 9 and 10 are each provided preferably with clip devices 11 and 12 having prongs 13 which permit the sections when separated to be secured to fabric or the like 14 as indicated in Fig. 10. The sections 5 and 6 when separated 5 may be used consequently as clips, and may be secured to a dress or other wearing apparel. The devices 11 and 12 are pivoted at 15 and 16 and are provided with notches adapted to register with detents 17 and 18 on the adjacent hubs so 10 that the devices are held in closed position, but owing to their resiliency may nevertheless be turned on their pivots to open the clips.

The member 9 is provided with a resilient projection 19 which is pivoted at 20 thereon and 15 is adapted to be folded rearwardly as indicated in Figs. 3 and 10, so as to be invisible when the device is used as a clip. The projection 19 is adapted to co-operate with a recess 21 in the member 10 and engages a shoulder therein to 20 hold the parts 9 and 10 in articulated relation. A fingerpiece 22 may be depressed to release the projection 19 from the shoulder when the sections 5 and 6 are to be separated. To prevent accidental separation, a safety catch 23 having a 25 prong 24 is pivoted on the member 10 at 25 and is adapted to be moved so that the prong engages an opening 26 in the projection 19 as clearly shown in Fig. 1. When the safety catch 30 is in place, sections 5 and 6 cannot be separated 30 even if the fingerpiece 22 is depressed.

At the opposite end of the section 6 a resilient projection 27 having fingerpieces 28 and 29 is pivoted at 30 so that it can be folded back into 35 invisible position behind the member 30' as indicated in Fig. 6. The projection 27 is adapted to co-operate with a recessed element 31 at the contiguous end of the section 5 engaging a shoulder therein as indicated clearly in Fig. 4. By depressing the fingerpiece 29 the parts may 40 be released. To avoid accidental separation, a safety catch 32 is pivoted at 33 and is provided with a prong 34 which is adapted to engage between the two sides of the projection 27 as indicated in Fig. 5. The safety catch is held in 45 position by a finger 35. Consequently the sections 5 and 6 cannot be detached from each other until the safety catch is released.

When all of the parts are assembled in the 50 manner described, a complete bracelet is formed. It may be opened if desired, to secure it upon the arm of the wearer, and then closed by manipulating the catches. When the parts 5 and 6 are to be used separately, the opposite ends of the sections 5 and 6 are detached from each other 55

and the projections 19 and 27 are folded back as indicated particularly in Figs. 6 and 10, so that they are concealed. Thereupon the sections 5 and 6 may be secured by the clip devices 11 and 5 12 to a dress or other garment of the wearer and will be securely held as ornaments thereon. The parts may be reassembled as readily to form again a complete bracelet.

Although the invention has been described as 10 a bracelet comprising two detachable sections adapted to be used as clips, it is apparent that three or more sections can be provided and that other types of fastening devices can be secured to the separate sections whereby such sections 15 can be used when detached in various ways for decorative purposes.

Various changes may be made, therefore, in the 20 details of construction and arrangement of the parts without departing from the invention or sacrificing any of the advantages thereof.

I claim:

1. A bracelet comprising articulated sections, means at the ends of the sections permitting detachment from the ends of contiguous sections, 25 and fastening means on the sections for attaching them to fabric and the like.
2. A bracelet comprising articulated sections, means at the ends of the sections permitting detachment from the ends of contiguous sections, 30 means for normally locking the sections in articulated relation, and fastening means on the sections for attaching them to fabric and the like.
3. A bracelet comprising articulated sections, means at the ends of the sections permitting 35 detachment from the ends of contiguous sections said means being adjustable to invisible position when the sections are detached, and fastening means on the sections for attaching them to fabric and the like.
4. A bracelet comprising articulated sections, means at the ends of the sections permitting 40 detachment from the ends of contiguous sections, means for normally locking the sections in articulated relation, said first mentioned means being 45 adjustable to invisible position when the sections

are detached, and fastening means on the sections for attaching them to fabric and the like.

5. A bracelet comprising a plurality of sections, means at opposite ends of each section co-operating to detachably engage and hold the sections 5 in articulated relation, and independent fastening means on the sections for attaching them to fabric and the like.

6. A bracelet comprising a plurality of sections, 10 means at opposite ends of each section co-operating to detachably engage and hold the sections in articulated relation, means for normally locking the co-operating means, and independent fastening means on the sections for attaching them to fabric and the like.

7. A bracelet comprising a plurality of sections, 15 means at opposite ends of each section co-operating to detachably engage and hold the sections in articulated relation, said means being adjustable to invisible position when the sections are 20 disengaged, and independent fastening means on the sections for attaching them to fabric and the like.

8. A bracelet comprising a plurality of sections, 25 means at opposite ends of each section co-operating to detachably engage and hold the sections in articulated relation, means for normally locking the co-operating means, said co-operating means being adjustable to invisible position when the sections are 30 disengaged, and means forming a part of at least one of said sections whereby it may be attached to fabric and the like.

9. A clip comprising a decorative facing, means pivotally attached to the facing to hold the clip 35 to fabric and the like and means secured to the ends of the facing, normally invisible and adjustable to articulate the facing to other clips.

10. A clip comprising a decorative facing, means pivotally attached to the facing to hold the clip to fabric and the like, means secured 40 to the ends of the facing, normally invisible and adjustable to articulate the facing to other clips, and locking means associated with the last mentioned means.

GASTON CANDAS. 45
